UNITED STATES PATENT OFFICE.

WILLIAM F. CLASS AND ERNST C. SCHWAN, OF CLEVELAND, OHIO, AS
SIGNORS TO SAID CLASS AND ROBERT SANDERSON, OF SAME PLACE.

VALVE-GEAR.

SPECIFICATION forming part of Letters Patent No. 309,333, dated December 16, 1884.

Application filed January 31, 1882. Renewed September 12, 1883. (No model.)

To all whom it may concern:

Be it known that we, WM. F. CLASS and ERNST C. SCHWAN, of Cleveland, in the county of Cuyahoga and State of Ohio, have invented 5 certain new and useful Improvements in Valve-Gear for Steam-Engines; and we do hereby declare the following to be a full, clear, and exact description of the invention, such as will enable others skilled in the art to which it pertains to make and use it, reference being had to the accompanying drawings, which form part of this specification.

Our invention relates to an improvement in steam-engines; and it consists, first, in an oscillating valve which is cut away upon opposite sides, and which has an opening through its center which communicates with an opening through one end of its stem, through which the exhaust-steam escapes; second, in the combination of an oscillating valve of suitable construction, a pivoted rocking lever which shifts the valve back and forth, and which lever is operated by means of a sliding rod which is connected to the piston.

25 The object of our invention is to provide an oscillating valve which allows the water or steam to entirely surround the valve in the valve-chamber to prevent any side pressure or friction, and which is made to exhaust the water and steam through its center and one end, so that there will be neither side nor end pressure produced upon the valve.

Figure 1 is a side elevation of my invention complete, the valve-chamber being seen in section. Fig. 2 is a plan view of the mechanism for shifting the valve. Fig. 3 is a vertical cross-section of the valve. Fig. 4 is a longitudinal vertical section of the same.

A represents the cylinder, and B the piston-rod, which is connected to the piston in the usual manner. Connected to each head of the cylinder is an inlet and outlet pipe, C, through which the steam or water by which the engine is to be operated is both taken into the cylinder and exhausted therefrom. Each one of the pipes C is made in two parts, and these parts are connected together by means of a flanged coupling, E, so that the valve and valve-connection can be entirely removed from 45 the cylinder at any time that it may be de-

sired. This will be found a great matter of convenience in the transportation of the engine, for it will then take up much less room, and those parts of the valve which extend directly out from the valve-chamber can be cast 55 as a part thereof, and thus save the expense of couplings and connections at the side of the chamber.

The chamber F is made circular, and is provided with a stuffing-box at each end, where 60 the stem of the valve G projects through it. The valve G is cut away upon opposite sides, while only those two portions of the valve which have to make connections with the inlet and outlet pipes form a part of a circle. 65 By cutting away the sides of the valve, as here shown, the steam or water is admitted directly into the chamber, and fills the whole of the chamber around the valve at every point except at the two outlet-ports, which are in contact with the sides of the chamber. By thus having the water or steam around the valve as it passes toward the cylinder the pressure upon all sides is always exactly the same, and there is neither side nor end pressure to cause 75

any useless friction. The opening H, which is made directly across the center of the valve, is made to register with one of the pipes each time that the valve is made to shift, and thus the exhaust water or steam is made to pass directly into the center of the valve and escapes through the longitudinal opening I, which is made through one end of the stem of the valve, and which passes outside of the chamber, and has any suitable connecting-pipe to carry off the 80 steam or water. As the exhaust steam or water is taken directly into the center of the valve, it can produce neither side nor end pressure, and hence it is evident that the only friction ex- 85

erted upon the valve-rod is by the stuffing-box 90 at each end of the chamber for the purpose of making a tight joint. In order to enable the valve to form a perfect cut-off at each time that it is shifted, one of the inlet and outlet pipes is connected to the side of the cylinder slightly 95 below the other, the difference in height between the two being about three-sixteenths of an inch.

Secured to the solid end of the stem of the valve is the cranked arm L, which, extends 100

downward, and against which arm the projections N on the segment O are made to strike for the purpose of shifting the valve at every stroke of the piston. This segment is secured 5 to or cast with the lever P, which is pivoted upon the top of the bed-plate, and which lever is caused to shift back and forth upon its pivot by the sliding arm Q, which is provided with suitable projections, R. This sliding arm 10 Q is fastened to the piston-rod, and is held in suitable guides, S, which are attached to the cylinder-heads. At each stroke of the piston one of the projections upon this sliding arm strikes against the side of the lever, and 15 causes the lever to swing over toward the other side of the center of its pivot, and as the pitman returns the lever is forced back again, and at each movement the valve is shifted so as to exhaust one end of the cylinder. Where 20 steam is used, there is no need of an extension of the lever beyond the segment, for the quick movement of the sliding arm will force it back and forth over its center; but where water is used as a motive power, the movement being 25 so much slower, a weighted arm is fastened to the upper end of the lever. This weight is necessary for the purpose of carrying the lever past its center.

Upon the outer side of the gland for the 30 stuffing-box there are formed two arms or projections, which serve to regulate the distance that the cranked arm of the valve shall move, and this cranked arm serves as a stop to limit the movement of the rocking lever. The slid-

ing rod may be provided with movable projections, so that they can be moved nearer together or farther apart, according to the stroke desired, and thus be made to shift the valve more slowly or quickly, as may be found necessary. 35

Having thus described our invention, we 40 claim—

1. The combination of the chamber F, connected upon opposite sides by means of pipes with the ends of the cylinder, and the valve G, having one of its ends made solid and the other 45 one hollow, so as to carry off the exhaust-steam or water, and having its sides cut away in such a manner that the chamber F is kept full of steam or water, so as to entirely surround sides 50 of the valve at all points except where the edges of the valve come in contact with the sides of the chamber, substantially as shown and described.

2. The combination of an oscillating valve which is provided with a cranked arm, a 55 rocking lever provided with a segment and projections for striking against the cranked arm, and a sliding rod which is connected to the piston-rod, the sliding rod being provided with projections for rocking the lever, substantially as specified. 60

In testimony whereof we affix our signatures in presence of two witnesses.

WILLIAM F. CLASS.
ERNST C. SCHWAN.
